Inventor:
E. M. Kinney

UNITED STATES PATENT OFFICE.

E. MCKINNEY, OF MONTGOMERY, OHIO.

IMPROVEMENT IN SEEDING-MACHINES.

Specification forming part of Letters Patent No. 25,025, dated August 9, 1859.

To all whom it may concern:

Be it known that I, E. MCKINNEY, of Montgomery, in the county of Hamilton and State of Ohio, have invented a new and Improved Seeding-Machine; and I do hereby declare that the following is a full, clear, and exact description of the same, reference being had to the accompanying drawings, making a part of this specification, in which—

Figure 1 represents a longitudinal vertical section of my invention, the line $x x$, Fig. 2, indicating the plane of section. Fig. 2 is a plan or top view of the same. Fig. 3 is an end view of the same. Fig. 4 is a detached face view of my spacing-wheel.

Similar letters of reference in all the figures indicate corresponding parts.

This invention consists in arranging the distributing-disks in combination with check-valves, and with a bell and hammer, in such a manner that the time when the check-valve opens and when the corn is deposited on the ground is indicated by the stroke of the hammer against the bell, whereby the operator is enabled to plant his seed or corn in check-rows, so that it can be plowed both ways; and by a simple arrangement of a button, whereby the lever which operates the check-valve can be forced back, so that it keeps the check-valve always open, the dropping is changed into drilling.

To enable those skilled in the art to fully understand, make, and use my invention, I will proceed to describe its construction and operation.

The main frame A of the machine, which is constructed in a rectangular form in the usual manner, rests on two large driving-wheels, B B, which are rigidly attached to their axle C. This axle has its bearings in two lugs, a, which are secured to the under side of the horizontal side timbers of the frame, and a cog-wheel, D, is arranged on this axle in such a manner that a longitudinal sliding motion can be given to the same, independent from the rotary motion of the axle, which is communicated to the wheel by means of a key, or in some other convenient manner. This wheel gears into a horizontal spacing-wheel, E, which is attached to a vertical shaft, b, the lower bearing of which is in a cross-board, c, which is attached to the inside frame, F, of the machine; and its upper bearing is in a bridge-piece, d, the position of

which is strengthened by a brace, e. The inside frame, F, swings on pivots f in the longitudinal side timbers of the main frame A, and secured to its front part is the foot-board G, which serves to raise the back end of the swinging frame F, and this foot-board is adjustable by means of an arc, g, which is rigidly attached to the main frame, and which is provided with a number of holes, whereby the back end of the swinging frame can be adjusted, as will be hereinafter more fully explained.

Attached to the shaft b, close over the wheel E, is a band-wheel, H, and a handle, I, is fastened to the upper end of this shaft, which is situated close before the driver's seat J, which is supported by a cross-board, J', which is rigidly secured to the main frame A.

The hopper-boxes K are secured to the back end of the swinging frame F, and the seed is distributed by disks L, each of which is provided with six seed-cells, h, and which receive a rotary motion by means of a bevel-gearing, i i', the wheels i being secured to the lower ends of the pivots on which the disks rotate, and the wheels i', of equal size with the wheels i, being attached to a horizontal shaft, k, which bears a band-wheel, l, and to which motion is communicated by means of a band, m, from the band-wheel H. A pin, n, is secured in the sides of the band-wheel l, which strikes against the upper end of the handle of a hammer, o, so that the same is caused to strike against a bell, M, once for every revolution of the shaft k and of the disks L. Each of these disks is provided with a projecting pin, p, which serve to operate the levers N, which connects with the check-valves q. These valves are arranged in slides r, attached to the lower end of the reservoirs O, and from these reservoirs the discharge-tubes P extend down to the toes Q, which are provided with two flange-covers, s s', attached to each, set at such an angle that the front ends will gather the loose dirt together and leave it in a light ridge immediately behind the planting-toe. These toes are secured to a horizontal bar, R, which is supported by pins r' in sockets S, so that it is free to rise when the toes meet with some obstruction, being kept down by the action of springs. Suspended from the bar R are also the shares T, in such a manner that they can be adjusted sidewise so as to be nearer to or

farther from the toes Q, according to the distance or width of the furrows.

In order to be able to keep the levers N in such a position that the valves q are closed, springs t are brought to bear on the upper parts of the same, and in case it is desired to have the valves open the levers are turned back by means of buttons u.

The wheel E is arranged with three or more rows of cogs, v, v', and v'', all of an unequal pitch, so that the cog-wheel D can be brought to gear in either one of the rows; and it is obvious that the distributing apparatus is operated quicker when the cog-wheel B is in gear with the inner row of cogs, v'', and slower when it is brought to gear into one of the outer rows, v or v'. The position of the wheel D is indicated by an index, w, which is attached to the hub of the wheel, and which swings over marks y, y', and y'' on the side of the driver's seat.

The operation is as follows: After the driver has taken his seat he raises the back end of the swinging frame F, together with the distributing apparatus and with the shares, until he arrives on the field, when he lets down the frame F and adjusts it to the depth to which he intends to draw his furrow by means of the foot-board G and arc g, and by driving across the field the planting is effected. If the diameter of the driving-wheel is equal to twelve feet, and if the wheel D has eighteen cogs, and the number of cogs in the rows v, v', and v'' of the spring-wheel E is twenty-four, twenty-one, and eighteen, and if the diameter of the band-wheel H is four times as large as the band-wheel l, the hills are planted at forty-eight inches apart when the wheel D is brought to gear into the outer row of cogs, v, of the spacing-wheel, and at forty-two inches when brought into gear with the second row, and at thirty-six inches when gearing into the last row of cogs, and as each of the seed-cells h, in the distributing-disks L takes one kernel only, six kernels will be carried into each of the reservoirs O during each revolution of the disks, and whenever the check-valves are opened, which is once for every revolution of the disks, the contents of the reservoirs are discharged to the ground. The number of seeds in a hill will be regulated by slides on the disks, or simply by stopping up some of the holes with a cork, and it may be varied from one to six, and for each revolution of the disks the hammer strikes against the bell, so that the driver knows the exact time when the hill is planted. When the levers N are depressed by turning the buttons u, so that the check-valves q are always open, the dropping is changed into drilling, and the machine, with

all the seed-cells in the disks open, will deposit the kernels at distances at six, seven, or eight inches in the row, according to the position of the cog-wheel D, and with each alternate seed-cell in the disks stopped up it will drill at twelve, fourteen, and sixteen inches in the row. The covered position of the cog-wheel D is pointed out by the index w, and if this index stands right opposite to one of the marks y, y', and y'', the cog-wheel is in gear with one of the rows of cogs v, v', or v'' of the spacing-wheel. If, however, the index is between two of these marks, the cog-wheel is between two of the rows of cogs of the spacing-wheel and the machine will be out of gear. In this position the machine can be operated by hand by turning the crank I, and the seed can now be distributed as fast or as slow as may be desirable. This crank also serves to insure the coincidence of the rows. To do this the driver must watch for the last stroke of the bell at the end of the row he is planting, when he marks the place with his foot, and he then throws the machine out of gear until he turns into the next row and stops with the toe Q opposite the hill last planted, when, by turning the crank until the bell strikes, another hill will be planted exactly opposite the last in the previous row, and now he lets the machine drop into gear and drives on, and each following hill will coincide exactly with the hills in the row previously planted.

The space between the rows is regulated by shifting the planting-toes Q laterally on the beam R, which is necessary, as some persons plant their corn four and others three feet apart between the rows, and in the case of broom-corn, chocolate-corn, or Chinese sugar-cane, if desired, the machine will put in the seed still closer. When done planting, or if the driver desires to drive to a neighboring field, he can raise the back end of the swinging frame F at any instant by straightening his legs and bearing against the foot-board G, whereby the working parts of the machine are raised from the ground and the wheel E is thrown out of gear with the cog-wheel D.

Having thus described my invention, what I claim as new, and desire to secure by Letters Patent, is—

The within-described arrangement and combination of the distributing-disks L, levers N, check-valves q, and buttons u, to operate together with the hammer o and with the bell M, substantially as and for the purpose set forth.

E. MCKINNEY.
